UNITED STATES PATENT OFFICE.

JOEL AMES, OF MONTROSE, IOWA, ASSIGNOR OF ONE-SIXTH TO LINCOLN C. MILLER AND ONE-EIGHTH TO GIBSON BROWN, BOTH OF KEOKUK, IOWA, ONE-EIGHTH TO JOHN C. SCHEE AND ONE-EIGHTH TO THOMAS S. ROBINSON, BOTH OF FARMINGTON, IOWA, AND ONE-EIGHTH TO EDWARD LEECH, OF MONTROSE, IOWA.

TRAIN-CONTROL SYSTEM.

1,118,892.

Specification of Letters Patent.

Patented Nov. 24, 1914.

Application filed April 12, 1913. Serial No. 760,799.

To all whom it may concern:

Be it known that I, JOEL AMES, a citizen of the United States of America, residing at Montrose, county of Lee, State of Iowa, have 5 invented a certain new and useful Train- Control System, of which the following is such a full, clear, and exact description as will enable any one skilled in the art to which it appertains to make and use the 10 same, reference being had to the accompanying drawings, forming part of this specification.

My invention relates to an electrically operated system for automatically warning 15 and controlling trains to prevent collisions, and derailments due to defects in the track, and its object is to produce a system of this character which will be reliable and positive in its operation. The system may be used 20 either on steam or electric railways.

Broadly, my invention consists in providing an arrangement of circuits whereby a train controlling circuit, including means for controlling any desired signal or brake 25 controlling device on the train, is constantly maintained as the train advances along the track. A local circuit, or circuits, on the train may be so arranged that when the train controlling circuit is interrupted on 30 account of the too close approach of another train, or through a broken wire, or a defective battery or connections, a warning signal or the airbrake, or both, will operate.

Referring to the drawings, Figure 1 is a 35 diagrammatic representation of the track, contact rails and the arrangement of the main circuits of the system; Fig. 2 shows means for protecting trains against open switches, or cars, or trains which come into 40 the block from a side track; Fig. 3 sets forth one arrangement of circuits and signal devices carried by the train; Fig. 4 is a view showing the position of the contact shoes on the train and the disposition of 45 contact rails at crossings and the like; Fig. 5 shows the electrical connections between contact rails and contact shoes; Fig. 6 is a fragmentary view, partly in section and partly in elevation, showing the contact 50 shoes and contact rails and one method of supporting each; Fig. 7 is a plan view of the contact shoe shown in Fig. 6; Fig. 8 shows another arrangement of circuits on

the train for the same general purpose as the arrangement shown in Fig. 3.

1 and 2 represent the rails of a track which are divided into insulated sections or blocks.

3 and 4 are contact rails also divided into insulated sections, preferably corresponding 60 in length to the length of the track sections. For convenience in showing the circuits, these rails are shown separately in Figs. 1 and 2—in practice, these rails may be placed one above the other as shown in Fig. 6.

17, 18, 19, 20 and 21 are relays, each of 65 which is in circuit with the track rails of a section and with a track battery 12 forming what I will designate as track circuits.

5 is a conductor extending along the track 70 and connected to a track rail of each section or block.

13 and 14 represent trains on the track, each of which is provided with at least one contact shoe 15 and with a battery or other 75 source of electrical energy 26. Each section of each contact rail is connected through the armature of a relay to one of the track rails. The relay in each track circuit controls two armatures, one of said 80 armatures being in circuit with a section of contact rail 3 and the other being in circuit with a section of contact rail 4.

Referring to Fig. 3, the train carries a 85 partial circuit for establishing connection between one of the contact rails and one of the track rails, this partial circuit in Fig. 3 comprising contact shoe 15, a quick acting relay 25, a slow acting relay 24, battery 26 and a truck of the train. The slow acting 90 and quick acting relays control apparatus on the train which will be hereinafter described.

The operation of the system as shown in Fig. 1 will now be explained. The relays 95 17, 18, 19, 20 and 21 are normally energized by the batteries 12, and their armatures are held in the closed or attracted position. When a train is on a block, however, the battery of the block will be short-circuited 100 through the trucks of the train and the armatures of the relay in the track circuit of that block will be retracted under the influence of their springs, and the circuits of which they are a part will thereby be opened. 105 In Fig. 1, a train is shown in block 8 and

also in block 10, and the armatures of relays 18 and 20 are therefore in the open position and no circuit could be established which included the sections of contact rail 3 in blocks 7 and 9 or the sections of contact rail 4 in blocks 9 or 11. In this system, trains traveling in the same direction as train 14 have their contact shoes bearing on contact rail 4 and trains which travel in the direction of train 13 have their contact shoes bearing on contact rail 3. In the positions shown, trains 13 and 14 each establish a complete train controlling circuit. With reference to train 14, this circuit may be traced as follows: from battery 26 to contact shoe 15, to contact rail 4, armature of relay 19, conductor 5, track rail 2 and the truck of the train, to battery 26. Supposing that train 14 reaches block 9 while train 13 is still on block 8, it would be unable to establish a complete train controlling circuit for the reason that the circuit, in this position, would comprise the section of contact rail 4 in block 9 and an armature of the relay 18. This armature, however, remains in its opened position as long as a train is on block 8. It will also be clear that a broken rail will prevent the energization of the relay in the track circuit of the same block and thereby permit the armatures of this relay to open, and thus make it impossible for a train on either block or the adjacent blocks to establish a complete train controlling circuit.

When, for any reason, a complete train controlling circuit can not be established by a train, the apparatus shown in Fig. 3 becomes operative to warn the engine man and also to automatically stop the train. In this figure, a circuit is shown which comprises battery 28, electromagnet 30, and the armatures of relays 24 and 25 which are in the train controlling circuit. As long as the train controlling circuit is complete, battery 28 sends current through relays 24 and 25 which hold their armatures in attracted position and keep the local circuit closed. When, however, both of these relays release their armatures, this local circuit is opened and the armature of relay 36 is retracted, thereby opening valve 36 in the air pipe connected with a train air pipe 33. The local circuit also contains the lamp 39 connected in parallel with an electromagnet 30. This lamp will be lighted while the local circuit is closed and will indicate to the engine man that the train is maintaining a complete train controlling circuit and that the track ahead is therefore clear. If the light does not burn, it indicates either that the apparatus is not in order or that there is danger ahead. As a further warning to the engineer of a break in the train controlling circuit, a whistle 37 may be provided to be operated

by the air which escapes when the valve 36 is opened, and also an additional local circuit comprising a bell or other warning device 32 and battery 31 may be operated by relay 27, in the manner shown.

It may sometimes happen that the connection between the contact shoe and the contact rail may be broken momentarily when there is otherwise a complete circuit for the train and to avoid unnecessary stopping of the train on this account, the slow acting relay 24 is provided. It will be noted that the local circuit on the train will not be opened unless armatures of both relays 24 and 25 are open. If connection between the contact shoe and the contact rail is again established before the armature of the slow acting relay is retracted the quick acting relay 25 will again attract its armature with the result that the local circuit on the train will remain closed.

If the train is traveling slowly at the time it receives a warning, it is not necessary that it be automatically stopped and for that reason, I have provided a centrifugal device 34 driven from the car axle by a chain or belt 38, and which controls a valve 33. This device may be so adjusted that when the speed of the train does not exceed five or six miles an hour, for example, that valve 33 will be held closed with the result that the opening of the valve 36 which takes place when the main train controlling circuit fails, will not operate to release the air from the train pipe 35.

In Fig. 2, I have shown the circuit arrangement I provide at track switches. The insulated joints are placed in the contact rails 3 and 4 near the switch, but the two parts of these rails are nevertheless normally electrically connected by means of the switch 22 when the track switch is closed. When the track switch is open, this connection is broken with the result that if there were any train in the block at the time, its train controlling circuit would be broken and it would be warned or stopped. It will also be noted that should a train come on the track from a side track, that it will short-circuit the track battery 12 and cause the armatures of the relay in the track circuit to be released, thereby warning any train that may be in either of the adjacent blocks.

Fig. 8 shows another possible form of circuits on the train for the same general purpose as those shown in Fig. 3. Relay 45 in the portion of the train controlling circuit carried by the train is a quick acting relay. Relay 47 in the local circuit is preferably a slow acting relay, and 49 is also a slow acting relay. These relays are so arranged that they are constantly supplied with current from the battery 28 as long as the armature of relay 45 is closed. When this armature

opens, however, the armature of relay 47 will open, and, later, the armature of relay 49. When both of these last mentioned armatures have opened, the circuit through the relay 30 and the lamp 29 will be broken with the same result as in Fig. 3. All of the relays controlling the local circuit may be quick acting and the time required for opening the local circuit can be regulated by connecting a varying number of relays in the circuit in the same manner as relays 47 and 49 are connected. Resistances 48 may be proportioned to properly divide the current and the resistance 46 may be used to control the strength of the current in the main train controlling circuit.

In Fig. 2, I also show an electrically operated signal or semaphore 23 connected in parallel circuit with the track relay and also operated by the track battery. These semaphores may be placed at each end of the block and serve as additional means of notifying the engineer before entering a block whether the block is clear.

Referring to Figs. 4, 5, 6, and 7, 40 is a support for the contact rails 3 and 4 which are insulated from each other and from the support, as shown. 15 represents a contact shoe having bracing arms, slidably mounted on rods 43 and 44 carried by a bracket 41. The springs 42 tend to keep the contact shoe in a position midway between the upper surface of the upper contact rail and the lower surface of the lower contact rail, as shown in Fig. 5. An opening must be made in the contact rail at road crossings and in order that the train controlling circuit may not be broken when the train passes crossings, I provide a train with two contact shoes which may be located as indicated in Fig. 4 and which are electrically connected as shown in Fig. 5. The ends of the upper and lower contact rails are also electrically connected, as shown in this figure. The shape of the ends of these rails is such that after passing the crossing, a contact shoe will again engage with the same rail.

It will be noted that in the system herein described, the operative circuits are normally closed with the result that a defect in the apparatus such as broken wires or exhausted batteries will have the same effect as the too close approach of another train, thereby making the system a thoroughly safe one. The blocks may be made of any desired length, and a telephone circuit for communicating with the train from stations may be provided in transformer relation with the train controlling circuit, in the same manner as described in my application, Serial No. 706,939, filed July 1, 1912. The contact rails may be placed on one side of the track throughout a part of the block, and on the other side of the track throughout the remainder of the block where this

arrangement is desirable on account of the location of stations or for other reasons. When the contact rails are disposed in this manner, however, the train should be provided with two contact shoes, one on each side thereof.

I am aware that modifications may be made in the arrangement of conductors and other details of the apparatus described and I do not, therefore, desire that the scope of my invention be limited otherwise than by the appended claims.

Having fully described my invention, what I claim as new and desire to secure by Letters-Patent of the United States is:

1. In a train control system, the combination of a track having at least one of its rails divided into insulated sections, track circuits each comprising a source of electrical energy and an insulated track section, two contact members adjacent to each other and extending along the track, said contact members each being divided into insulated sections of substantially the same length as the corresponding track section, a contact device carried by a train and movable on its support whereby it may be caused to coöperate with either contact member, partial circuits for controlling trains each of said circuits comprising an insulated track section and a section of a contact member, and a switch in each train controlling circuit, said switch being controlled from a track circuit.

2. The combination in an electric train controlling system, of a railway track, two contact members, one above the other and extending adjacent to the track, a contact device carried by a train and capable of vertical movement, said contact device having upper and lower contact surfaces whereby it may coöperate with either contact member, and train controlling conductors comprising said contact device and contact members.

3. The combination with a railway track, of two contact members one above the other extending parallel to the track and terminating at crossings and the like where the end of the lower contact member on one side of the crossing is turned up and the end of the upper contact member on the other side of the crossing is turned down, a contact shoe carried by a train and so mounted as to be movable vertically, the positions of the ends of the contact members being such with relation to the normal position of the contact shoe that when the train moves in one direction from a position in which the contact shoe engages neither contact member, it will engage the upper contact member, and when the train moves in the opposite direction, the shoe will engage the lower contact member.

4. In a train control system, the combination of two contact members extending adjacent to the track and terminating at crossings and the like, conductors for connecting

each contact member with the corresponding contact member on the other side of the crossing, two contact shoes carried by a train and each adapted to coöperate with either 5 contact member, said contact shoes being spaced a greater distance apart than the distance between the ends of the contact members at said crossings, and electric train controlling means comprising said contact members and contact shoes.

5. In a train control system, a track divided into insulated sections or blocks, a track circuit for each section comprising track rails, a source of energy and a circuit 15 controlling device, two contact members extending adjacent to the track and divided into insulated sections corresponding in length to the track sections, a conductor extending adjacent to the track and connected 20 to a track rail in each block, partial train controlling circuits comprising a portion of said conductor, a section of a contact member, and a track rail, and means carried by a train for electrically connecting a track 25 rail and a contact member to form a complete train controlling circuit.

6. In a train control system, a track divided into insulated sections or blocks, a track circuit for each section comprising a track rail, a source of energy and a circuit 30 controlling device, two contact members extending adjacent to the track and divided into insulated sections corresponding in length to the track sections, a conductor extending adjacent to the track and connected 35 to a track rail in each block, partial train controlling circuits comprising a portion of said conductor, a section of a contact member and a track rail, means carried by a train for electrically connecting a track rail and a 40 contact member to form a complete train controlling circuit, and a switch operated by the circuit controlling device for making an opening in two partial train controlling circuits. 45

In testimony whereof, I have hereunto set my hand and affixed my seal.
